CARL FRITZ SJÖMAN AND CARL GUSTAF PETTERSSON, OF STOCKHOLM, SWEDEN, AS
SIGNORS TO J. & C. G. BOLINDERS MEKANISKA VERKSTADS AKTIEBOLAG, OF
STOCKHOLM, SWEDEN.

FUEL-INJECTING NOZZLE.

Application filed July 13, 1923, Serial No. 651,360, and in Sweden March 1, 1923.

This invention relates to such fuel injecting nozzles, in which a movement is imparted to the fuel before the injection, said movement performing spraying of the fuel jet when leaving the outlet opening of the nozzle. The object of the invention is to facilitate adjustment of the magnitude of the spraying.

This is obtained according to the invention by dividing the fuel before the injection in different currents or groups of currents, which perform each a spraying of the fuel, but are brought mutually by adjustment to counter-act each other as to their spraying action. By this it will be possible to adjust with great accuracy the angle of spread of the jet. If, for instance, the one current or group of currents is caused to act undisturbed by the other, the widest angle of spread of the jet is obtained. However, as soon as on the other hand the counter-acting current or group of currents is brought into action, the angle of spread of the jet will decrease on account of the counter-action, and if the currents or groups of currents counter-acting each other be equal as to the strength, the movement performing the spraying will cease and the fuel will be injected without spraying, i. e. as a straight jet.

The adjustment may be performed by varying the strength of but one of the currents or groups of currents or of both. The former case, in which the one current or group of currents remains constant, has proved to be the most suitable and simple for the object in view.

An embodiment of the device suitable from constructional point of view consists in providing the nozzle with two fuel conduits leading both to a cavity located inside the outlet of the nozzle and into which the conduits open tangentially or in such other way obliquely that the fuel will be brought to rotate within the cavity. The channels from the one conduit are directed towards the channels from the other conduit so that the fuel currents from both conduits will counter-act each other. By means of a throttling device in the one conduit the strength of the current from said conduit may be adjusted, i. e. the counter-action of the current may be made more or less strong

so that the spraying of the fuel will be varied accordingly.

The annexed drawing shows the invention carried out in the manner set forth above. Fig. 1 is a longitudinal section of the nozzle. Fig. 2 is a similar view on an enlarged scale of the portion of the nozzle situated next to the outlet opening. Fig. 3 shows the nozzle viewed from the outlet end with the outer part in section.

Disposed immediately inside the injection opening 1 of the nozzle is a cavity 2, into which the fuel currents or groups of fuel currents counter-acting each other are conducted. The separate conduits for the said currents are arranged in the following manner. A sleeve 3, in the bottom of which the injection opening 1 is provided, encloses a sleeve 4 into which projects an adjustable spindle 5 provided with a valve member 6, bearing against a seat in the sleeve 4. The said sleeve is of greater diameter than the spindle so that a chamber 7 will be formed between said parts, said chamber communicating through openings 8 in the wall of the sleeve 4 with a chamber 9 located between the spindle and an outer surrounding sleeve or body 10. The sleeves 3, 4 and 10 conjointly form a body means for the delivery of the spray. When the valve 6 is according to the drawing pressed onto its seat, the chamber 7 between the spindle 5 and the sleeve 4 is closed from a chamber 11 located in the sleeve, channels 12 leading from the said chamber 11 to channels 13 on the outside of the sleeve 4 and said latter channels communicating with channels 14 disposed on the conical end surface of the sleeve 4 and opening into the cavity 2 in a direction obliquely to the radius.

Thus, the chamber 9, the openings 8, the chamber 7, the chamber 11 and the channels 12, 13 and 14, respectively, form the conduit for one of the two counter-acting fuel currents and said conduit may be closed or opened to the desired degree by turning the valve spindle 5.

The conduit for the other fuel current consists of longitudinal channels 15 formed on the outside of the sleeve 4 and communicating at their outer ends with channels 16 formed in the conical end surface of the sleeve 4. The last mentioned channels,

which open also into the cavity 2, are, as apparent from Fig. 3, directed obliquely to the radius, so as to bring the fuel to rotate within the cavity. Besides, they are, however, directed towards the oblique channels 14, so that the fuel currents through said latter channels will be counter-acted by the currents through the channels 16. The inner ends of the channels 15 communicate 10 with a chamber 18 situated between the sleeves 3 and 4 and communicating with the chamber 9, which communicates in ordinary manner with the inlet 17 through which the fuel is supplied under pressure.

15 The device acts in the following manner: When the valve 6 is closed, as shown in the drawing, the fuel passes from the inlet 17 and the chamber 9 through the chamber 18 and the channels 15 and 16 to the cavity 2, in which the fuel is caused to rotate in the direction of the arrow *a*, Fig. 3, due to the oblique position of the channels 16. On account of the said rotation the jet forced through the opening 1 is sprayed as soon as 20 it leaves the said opening. In this case the spraying is the greatest possible. If the spraying is to be decreased, the valve spindle 5 is turned so that the valve will open. Hereby, the counter-acting fuel conduit is 25 opened and the fuel passes through the openings 8, the chamber 7, the chamber 11 and the channels 12, 13 and 14 to the cavity 2. On account of the channels 14 being directed obliquely and towards the channels 30 16, the fuel current through the channels 14 will put the fuel in rotation in the direction of the arrow *b*, Fig. 3. Thus, the current through the channels 16 will be counter-acted and the spraying action decreased correspondingly. If the fuel currents through the channels 14 and 16 be of 35 the same strength, the rotation will be wholly checked and the fuel will be ejected as a straight jet. Thus, the adjustment may 40 be performed at any time through simply turning the valve spindle 5.

The throttling member may, if desired,

be arranged in any suitable manner in the conduit 18, 15 instead of in the conduit 8, 7, 11, 12, 13 and 14, or both of the conduits 50 may be provided with throttling members.

What we claim as new and desire to secure by Letters Patent of the United States of America is:—

1. A nozzle including body means having 55 a discharge opening therein and a chamber adjacent and communicating with said opening; passages in said body means dividing the liquid passing therethrough into a plurality of streams, and means adjacent 60 said chamber for producing whirling motions of the streams of liquid entering said chamber, the whirling motions of the respective streams being opposed to one another and arrested by mutual counteraction 65 prior to the discharge of the liquid from the body means, means for controlling the passage of liquid through certain of the passages for varying the counteraction of the whirling motion of one stream to the other 70 whereby to vary the angle of spread of the jet issuing from the discharge opening.

2. A nozzle comprising a body, inner and outer hollow members arranged one within the other and carried by one end of the body, the outer member having a discharge opening therein and said members being arranged in spaced relation to provide a chamber in communication with the discharge opening, groups of oppositely inclined oblique channels between the members, opening into said chamber, means for conducting liquid from the interior of said body between said members to certain of the inclined channels, means for conducting liquid from the interior of the inner member to the oppositely inclined channels, a valve controlling the admission of liquid to the interior of the inner member. 85

In testimony whereof we affix our signatures.

CARL FRITZ SJÖMAN.
